(57) **CLAIM**

The ornamental design for a video conference system, as shown and described.

DESCRIPTION

FIG. 1 is a top and left elevational view of a video conference system;

FIG. 2 is a right side elevational view;

FIG. 3 is a front elevational view thereof;

FIG. 4 is a rear elevational view thereof;

FIG. 5 is a bottom plan view thereof;

FIG. 6 is a top plan view thereof;

FIG. 7 is a left side elevational view thereof;

FIG. 8 is a right side elevational view thereof; and,

FIG. 9 is a right side elevational view of a display device shown in the preceding views.

The broken lines in the drawings depict environmental subject matter only and form no part of the claimed design.

The element depicted in FIG. 9 is shown separately for ease of illustration only.
